ESCAPEMENT MECHANISM OF TYPOGRAPHICAL COMPOSING MACHINES

Richard Henry Scott, Hale, and Arthur Staniland Hayward, Altrincham, England, assignors to Linotype and Machinery Limited, London, England, a British company

Application May 9, 1947, Serial No. 747,012
In Great Britain May 11, 1946

8 Claims. (Cl. 199—23)

1

This invention relates to the escapement mechanism of typographical composing machines, such as those known commercially under the registered trade-mark "Linotype," wherein escapement levers are actuated to release matrices from a magazine.

In known constructions of escapement mechanism, an escapement lever has been arranged to rock about an axis located outside its own marginal edges, the escapement lever being arranged to swing in a groove formed within a part of the matrix magazine and transverse rods or wires being used to guide or support a plurality of escapement levers. When it has been desired to remove an escapement lever for adjustment or replacement the presence of such support rods has been a source of inconvenience and has tended to prevent ready removal of the escapement lever.

The object of the present invention is to provide improved means for mounting and operating the escapement levers, such means being of simplified construction and facilitating ready access to any individual escapement lever.

According to the present invention, escapement mechanism for controlling the release of matrices from the magazine of a typographical composing machine comprises an escapement lever and means which serve the dual purpose of operating and supporting the escapement lever. Conveniently, such operating and supporting means is retractable to allow the escapement lever to be removed. The escapement lever may be supported by means which return the escapement lever from a matrix-releasing position to a matrix-holding position.

The escapement mechanism may comprise an escapement lever, mechanism for moving the escapement lever from a matrix-holding position to a matrix-releasing position and a spring-pressed plunger for returning the escapement lever to matrix-holding position, the escapement lever being supported by said spring-pressed plunger. The escapement lever is preferably supported on the side of the spring-pressed plunger.

For a detailed description of the invention, reference may be made to the accompanying drawings wherein the invention has been shown merely in a preferred form and by way of example. Obviously, however, many changes and variations may be made therein and in its mode of application which will still be comprised within its spirit. It is to be understood, therefore, that the invention is not limited to any specific form or embodiment, except insofar as such limitations are specified in the appended claims.

2

Referring to the drawings:

Figure 1 is a vertical section through the lower end of a magazine showing an escapement lever in normal position;

5 Figure 2 is a view similar to Figure 1 showing an escapement lever when operated for releasing the lowermost matrix contained in the corresponding magazine channel;

10 Figure 3 is a side view of the lower end of the magazine in its normal position in relation to the machine frame;

Figure 4 is a side view of the lower end of the magazine when the magazine is removed from the machine frame;

15 Figure 5 is an underside view, partly broken away, of the lower end of the magazine, and

Figure 6 is a partial transverse vertical section on an enlarged scale taken on the line VI—VI of Figure 1.

20 In the drawings, the invention is shown applied to a magazine 1 which is supported in position on the machine by a frame member 2 (see Figure 3). The magazine 1 carries at its underside members 3 (forming a so-called escapement bar) between 25 which the arc-shaped escapement levers 4 are located (see Figures 1, 2 and 5). Each escapement lever 4 is formed with pallets 5 and 6 and controls the release of matrices 7 from adjacent channels in the magazine 1, there being only one 30 such channel 8 illustrated in Figures 1 and 2.

Each escapement lever 4 is formed with a downwardly extending projection 9 against which a plunger 10 slidable in slots 3a in a member 3 is pressed (by the actuation in known manner of

35 a striker 11) to rock the escapement lever and release a matrix 7 from the magazine. On the other side of the projection 9 and slidable in slots 3a in a member 3 is a plunger 12 which is pressed against the projection 9 by means of a detachable 40 spring 13, so as normally to hold the escapement lever in the position indicated in Figure 1. The nose portion 14 of the spring-pressed plunger 12 is rounded at the end or is suitably shaped to co-operate with the projection 9. A part of the 45 convex under-surface of the escapement lever 4 rests on the flat upper surface of the spring-pressed plunger 12 (see Figure 6) so that said plunger forms a support or bearer for the escapement lever.

50 The upper or concave surfaces of the escapement levers engage with the convex surfaces 15a formed on a removable cross-bar 15 which acts as a guide during the rocking movement thereof. Banking surfaces 16, 17 formed in the concave 55 surface of each escapement lever come into con-

tact with the under-surface 18 of the magazine 1 when the escapement lever has been rocked from one position to another (i. e. to and from the positions indicated in Figures 1 and 2) and prevent any further movement or displacement of the escapement lever.

To release a matrix 7 from the magazine 1, the striker 11 is actuated to press against the plunger 10 which in turn presses against the projection 9 in opposition to the action of the spring-pressed plunger 12. The escapement lever is thus moved from the position shown in Figure 1 to the position shown in Figure 2 and the lowermost matrix 7 is released. During this movement the spring-pressed plunger 12 is moved back to the position indicated in Figure 2, and continues to act as a support or bearer for the escapement lever. The escapement lever subsequently returns to the position shown in Figure 1 in which the pallet 5 holds the succeeding matrix 7.

To remove any individual escapement lever 4 it is necessary only to retract the spring-pressed plunger 12 associated therewith (as indicated by the dot-and-dash lines in Figure 1) and the escapement lever can easily be withdrawn. If the machine is provided with a plurality of magazines 1 supported by frame members 2 which can be spread apart prior to the changing of a magazine, the removal of an escapement lever without removal of the magazine is further facilitated.

To prevent accidental operation of the escapement levers during the handling of a magazine for removal or replacement there is provided an escapement locking device of the kind comprising an escapement locking bar adapted to be moved out of and into active position as the magazine is applied to and removed from the frame member 2.

Referring to Figures 3, 4 and 5, the locking bar 19 is formed at each end with an extension 20 which engages the forked end 21 of a lever 22 pivoted at 23 to each side of a member 3. The other forked end 24 of the lever 22 engages a pin 25 on a lever 26 pivoted at 27 to each side of a member 3. A leaf spring 28 bearing on the forked end 24 of the lever 22 tends to hold the levers 22 and 26 in the position indicated in Figure 4. The lever 26 is formed with an offset portion 29 which engages the top surface 30 of the frame member 2 when the magazine 1 is supported in position on the machine. The engagement of the offset portion 29 with the surface 30 moves the levers 22 and 26 against the action of spring 28 to the position indicated in Figure 3 and so raises the locking bar 19 to an inactive position out of the paths of the plungers 10. When the magazine is removed from the frame member 2, the spring 28 moves the levers 22 and 26 to the position indicated in Figure 4 and the locking bar 19 is lowered into the paths of the plungers 10 to prevent actuation of the escapement levers 4.

Although the invention has been shown as applied to a magazine carrying at its underside the members or escapement bar 3, it will be understood that the invention is also applicable to a magazine of the kind in which the escapement bar 3 and escapement levers 4 are mounted in the machine independently of the magazine, and locking means carried by the magazine ensure that matrices are held therein during removal of the magazine from the machine.

Having described our invention, we declare that what we claim and desire to secure by Letters Patent is:

1. An escapement mechanism for controlling the release of matrices from the magazine of a typographical composing machine, said mechanism comprising, in combination, an escapement lever movable from a matrix-holding position to a matrix-releasing position and return, and a reciprocatory member to actuate the escapement lever in one direction, said actuating member being disposed below the escapement lever and presenting a supporting surface upon which said lever rests by gravity both when the lever is at rest and during its actuation.

2. An escapement mechanism for controlling the release of matrices from the magazine of a typographical composing machine, said mechanism comprising, in combination, an escapement lever movable from a matrix-holding position to a matrix-releasing position and return, and a reciprocatory member to actuate the escapement lever in one direction, said actuating member being disposed below the escapement lever and presenting a supporting surface upon which said lever rests by gravity both when the lever is at rest and during its actuation, and said member being mounted for retraction from its normal position to withdraw its support of the escapement lever and permit the lever to be removed.

3. An escapement mechanism for controlling the release of matrices from the magazine of a typographical composing machine, said mechanism comprising, in combination, an escapement lever movable from a matrix-holding position to a matrix-releasing position and return, a spring-loaded plunger to actuate the escapement lever in one direction, and a fixed guide in which the plunger is slidably mounted, said plunger at one end extending beyond its guide and below the escapement lever and presenting a supporting surface upon which said lever rests by gravity both when it is at rest and during its actuation.

4. An escapement mechanism for controlling the release of matrices from the magazine of a typographical composing machine, said mechanism comprising, in combination, an escapement lever movable from a matrix-holding position to a matrix-releasing position and return, a spring-loaded plunger to actuate the escapement lever in one direction, and a fixed guide in which the plunger is slidably mounted, said plunger at one end extending beyond its guide and below the escapement lever and presenting a supporting surface upon which said lever rests by gravity both when it is at rest and during its actuation, and said plunger being mounted within its guide for retraction from its normal position to withdraw its support of the escapement lever and permit the lever to be removed.

5. An escapement mechanism for controlling the release of matrices from the magazine of a typographical composing machine, said mechanism comprising, in combination, an escapement lever mounted to rock in a curved path and formed with a lower convex surface, and an actuating plunger having an upper bearing surface arranged in engagement with the lower convex surface of the escapement lever and upon which said lever rests by gravity.

6. An escapement mechanism for controlling the release of matrices from the magazine of a typographical composing machine, said mechanism comprising, in combination, an escapement lever mounted to rock in a curved path and formed with a lower convex surface, and an actuating plunger having an upper bearing surface arranged in engagement with the lower convex surface of the escapement lever and upon which

said lever rests by gravity, said actuating plunger being mounted for retraction from its normal position to permit the removal of the escapement lever.

7. An escapement mechanism for controlling the release of matrices from the magazine of a typographical composing machine, said machine comprising, in combination, an escapement lever mounted to rock in a curved path and formed at the front with a downwardly extending projection and at the rear with a lower convex surface, and a spring-actuated plunger slideable in a fore-and-aft direction to actuate the escapement lever, said plunger being arranged with its upper surface in engagement with the lower convex surface of the escapement lever to retain it removably in place and having a forward nose portion pressing against the downwardly extending projection on the escapement lever.

8. An escapement mechanism for controlling the release of matrices from the magazine of a typographical composing machine, said mechanism comprising, in combination, an escapement lever mounted to rock in a curved path and formed at the front with a downwardly extend-

5
